UNITED STATES PATENT OFFICE.

JAMES T. BROUH, OF JACKSONVILLE, FLORIDA.

CHAIN.

SPECIFICATION forming part of Letters Patent No. 245,780, dated August 16, 1881.

Application filed February 10, 1881. (Model.)

To all whom it may concern:

Be it known that I, JAMES T. BROUH, of Jacksonville, in the county of Duval and State of Florida, have invented a new and Improved 5 Chain, of which the following is a specification.

The flat-link chains in common use are made of links riveted together, the strength of the chain being determined by the quality and size of the rivets and their resistance to the shearing 10 strain or pull of the links, and when a link breaks one or two links have to be cut out and a new link put in, and new rivets also, which latter must be upset. Hence the operation of repairing a flat-link chain of ordinary construction 15 is slow and expensive.

The object of this invention is to facilitate the repairing and lengthening and shortening of flat-link chains.

The invention consists of a flat-link chain 20 having the thick or double link made with both faces recessed and socketed at each end, the socket being undercut, and in forming each single link with a flat-headed stud projecting at right angles from one face at each end thereof; and, further, in constructing the chain by 25 coupling the double and single links together by means of the engagement of the studs on the latter in the undercut sockets of the former.

Figure 1 is a front elevation of a double and 30 single link coupled together. Fig. 2 is a side elevation, partly in section, or with parts broken away, of a section of the improved chain. Fig. 3 is a front elevation of a single link. Fig. 4 is a front elevation of a double link. Fig. 5 is a front elevation, partly in section, showing the 35 manner in which the double and single links are coupled and detached from each other. Fig. 6 is a cross-section on line xx , Fig. 5. Fig. 7 is a cross-section on line yy , Fig. 5. Fig. 8 is a cross-section on line zz , Fig. 5.

Similar letters of reference indicate corresponding parts.

In the accompanying drawings, A represents a single link, one face of which is recessed or cut away, as shown at a , to diminish its weight, while from each end of the opposite and flat face, b , projects a stud, B, at right angles therefrom, said studs B having flaring or beveled heads, as shown at c , that have their outer edges

cut off, as shown at d , flush with the stud-shank 50 and at right angles to the longitudinal axis of said link A.

C represents a double link, whose opposite face-depressions, f , reduce its weight without materially diminishing its strength. At each 55 end of the central face-depressions, f , deeper depressions g are formed, that extend in opposite directions nearly to the ends of the said link C, and are undercut at their extremities, as shown at h , thereby forming sockets D for 60 receiving and holding the studs B of the single links A. The depressions g are of circular form, to permit the ready entrance of the heads c of the studs B, and are designed to be of the same depth as said heads c ; and as a depression, g , is 65 extended to a socket, D, it is continued straight on one side, as shown at l , for the easy passage or movement of the uncut edge of the stud-head c , while on the opposite side of the depression g a projection or stop, m , is formed to prevent 70 the admission or withdrawal of a stud, B, into or from a socket, D, excepting when the single link A is held at right angles to the double link C and the straight edge d of the head c is presented against the said projection or stop m , as 75 indicated in Fig. 5.

The links A C are coupled together by holding them at right angles to each other and inserting the stud B of the former into a depression, g , of the latter, and in then moving said 80 stud B, with its straight edge d against the stop m , into the socket D of the link C, and in turning said link A in line with the link C, so that the free end of the former shall extend beyond the latter. The projections or stops m are 85 formed in the four depressions g of each link C alternately in their opposite sides, as shown, so that each one of a pair of single links A, when coupling or uncoupling from a double link, C, may be turned in a different direction, as shown 90 in Figs. 5 and 7. Hence it will be seen that the impossibility of simultaneously uncoupling a pair of links, A, makes this chain more reliable than those now in use, and it will be seen that by no possibility could the links A C be moved 95 into the uncoupling position shown in Fig. 5 while the chain was in use; consequently they cannot get apart. Should a link break, it can be

quickly replaced, and the chain can be lengthened or shortened at will without the trouble of using or removing rivet or bolt.

In the manufacture of flat-link chains of ordinary construction the links have to be accurately drilled to a templet, which is slow and expensive work, or punched, which disturbs the fiber of the iron, so that the links are unfit for heavy work.

10 In the manufacture of the chain herein shown and described the links are all cast from steel or the strongest iron, and no drilling or punching is required to fit or hold them together. Hence the chain is cheaper, and broken parts 15 may be more quickly and cheaply replaced.

Having thus fully described my invention, I claim as new and desire to secure by Letters Patent—

1. In a chain-link, a double link, C, construct-

ed with undercut end sockets, D, depressions 20 *g*, and side projections, *m*, in combination with a single link, A, having the bevel-headed studs B cut off upon the outer edges of their heads in a perpendicular line with the stud-shanks, as and for the purpose described.

2. In a flat-link chain, the combination, with the single links A, provided with flaring or bevel-headed studs B, whose outer edges are cut off, as shown at *d*, of the double links C, having face-depressions *f*, *g*, and undercut end 30 sockets, D, substantially as herein shown and described, said double link and sockets being designed to receive and hold the single-link studs, as set forth.

JAMES THOMAS BROUGH.
